UNITED STATES PATENT OFFICE.

UMBERTO NOBILE, OF ROME, ITALY.

AIRSHIP OF THE SEMIRIGID TYPE.

Application filed September 2, 1922. Serial No. 585,925.

To all whom it may concern:

Be it known that I, UMBERTO NOBILE, a subject of the King of Italy, and resident of Rome, in the Kingdom of Italy, have invented certain new and useful Improvements in Airships of the Semirigid Type, of which the following is a specification.

This invention relates to improvements in the construction of semirigid airships provided either with a flat girder or with a tubular girder having a triangular or polygonal section.

In these types of airships the vertical and horizontal rudders hitherto have been usually arranged in such a way as to form a kind of biplane or a triplane cell directly connected to the framework or girder of the airship, which framework or girder in the case of airships with flat girder is to that end stiffened to a suitable extent towards the stern.

Said biplane or triplane cell presents two drawbacks:

1. It is not fit to satisfactorily withstand the torsional stress due to dissymmetrical loads on the planes;

2. From the aerodynamic point of view it opposes a greater resistance to flight, owing to the lateral position with respect to the envelope.

To obviate both of these drawbacks, according to this invention the said box is substituted by a cruciform system of wings, formed by stationary planes acting as keels, and by movable planes in alignment with the first mentioned ones and acting as rudders. This arrangement also has the advantage of relatively reducing the size of the movable planes.

Said cruciform system of wings is connected with the girder by means of an annular cage which is so shaped as to exactly follow the external outline of the hull of the airship, upon which it is arranged, whereby the shape of the cage and of the planes as well as the conformation of the envelope may be caused to vary particularly according to the size of the airship, and to other conditions resulting in practice from the peculiar method of construction adopted, such as for two different cases it is shown by way of example in the annexed drawings, in which—

Figs. 1 and 2 are a side elevation and an

end view, respectively, of an airship with the cruciform system of wings carried by an annular cage according to the invention;

Figs. 3 and 4 are a vertical diametral section and a plan view, respectively, of the stern end of a second embodiment of the system of wings according to the invention;

Figs. 5 and 6 are two cross sections along the lines X—X and Y—Y, respectively, of Fig. 3;

Fig. 7 shows a detail of construction;

Fig. 8 is an outer side elevation of a form of construction with a continuous gas bag within the annular cage;

Fig. 9 is a cross section along the line Z—Z of Fig. 8;

Fig. 10 is a detail of construction relating to the embodiment shown in Figs. 8 and 9.

As it is seen in Figs. 1 and 2 of the drawing, which refer to a first embodiment, the envelope —1—, to which the car —2— is connected in the usual way by means of rope suspensions —3— starting from the girder —4—, which rests upon or is fastened to the lower portion of said envelope, is stiffened towards the stern end by means of a system of rings —5—5'—5''— arranged according to the parallels of the envelope. These rings which, for instance, may be formed by steel tubes, are connected with the rigid portion 6 of the girder, which in the drawing has a triangular section, but which may also have a polygonal or even a curvilinear section. The connection of the annular elements —5— with the girder —6— may be effected either by means of hinges or rigidly.

The rings —5—5'—5''— are connected between each other by means of the girder, the keels —7—7'—7"—7'"— and by other longitudinal elements —8—. In this way on the hull of the airship is formed a network having large meshes. If it is deemed convenient, the stiffness of the whole system may be increased by providing diagonal elements in each one of the meshes.

It is to be remarked that the keel 7 is directly connected with the girder 6 so as to render it integral with the latter, thus increasing the stiffness thereof.

The four keels —7—7'—7"—7'"— are connected to the envelope —1— by means of a tying-up system shown in Fig. 7, for the

purpose of avoiding that the tubes or section irons or even the beams, of which the said rings or longitudinal elements are formed, project upon the surface of the envelope, thus diminishing the speed during the flight.

As it is seen in said Fig. 7, on the fabric 1 of the envelope are fastened the two fabric strips 10—10, which on the edges are 10 provided with eyelets. Upon approaching between each other the edges of the strips 10 by means of the tying-up system 11, the tube is so to speak immersed into the envelope, whereby on the outside a joined continuous surface, without any projections, is obtained.

Fig. 1 of the drawings shows also that in the form of construction represented therein the rigid portion 6 of the girder is 20 arranged inside the envelope so as to cause the plain wall of said rigid portion to form a continuation without interruption of the flat portion of the laminar girder. This arrangement of the rigid girder may be likewise provided at the bow, whenever it is deemed advisable to stiffen also the framework 12 in that part, thus limiting the flat girder 4 only to the central portion of the hull.

30 Another embodiment of the connection of the cruciform system of wings with the lower framework of the hull (no matter whether this framework be a completely rigid one, or formed of a flat girder) is that 35 shown in Figs. 3, 4, 5 and 6 and which suits better for airships having large dimensions.

Said embodiment differs from that shown in Figs. 1 and 2 in that the annular cage, instead of being limited to the section of 40 the girder carrying the keels, extends as far as to reach the extremity of the stern, for which purpose the longitudinal elements 8 are caused to extend up to said point and other rings 13—13' are added.

45 In this way at the stern is formed a complete cage which corresponds to that provided at the bow.

The section X—X, in which towards the stern portion ends the section, to which is 50 fastened the system of wings, is stiffened by means of a spider 14—15, Fig. 5. Also the keels, instead of being flat, are of a rigid structure, as it is seen in Fig. 6, which permits to obtain the advantage of strengthening the whole system, which thus requires a lesser number of connecting ropes.

Moreover, to obviate the inconvenience of the greater thickness of the keels, they are shaped in the way shown in Fig. 4, so as to 60 form no obstacle during the flight.

The insertion of the spider in section X—X makes it necessary to interrupt in that point the gas bag, in the chamber comprised between said section and the extrem-

ity of the stern being placed a separate gas 65 bag, whilst the metal cage formed by the rings and by the longitudinal elements is externally covered with fabric.

On the contrary, the envelope may be extended as far as to reach the extremity of 70 the stern by omitting, if necessary, also the rigid rear cage, as it is shown in Fig. 8. But in this case the envelope is to be provided (Figs. 9 and 10) with suitable fabric sleeves 16 to allow of the radial elements 14 75 of the rigid section X—X being passed through without diminishing the tightness of the envelope.

It is clear that, whatever of these two arrangements may be adopted, for simplicity's sake it will always be advisable to extend the compensating air chamber only as far as to reach the section X—X. But this is of no prejudice whatever, on the contrary it represents an advantage, and, as it is seen in Fig. 1, also in that form of construction with a free passage through the interior of the annular cage the extension of the air chamber 17 is limited towards the stern portion, that is to say it reaches only up to the point at which starts the rigid portion 6 of the girder.

With said arrangement in practice several advantages are attained:

1. The advantage of diminishing the 95 weight of the stern portion.

2. The advantage of diminishing the stress on the framework of the keel when the airship moves at a low height.

3. The advantage of permitting to more 100 easily maintain the longitudinal trim of the airship by turning to profit the circumstance that, by and by as the driving material available on board the airship is used up and the gas consequently expelled, the centre of thrust (centre of the volume of gas) 105 is shifted towards the bow portion.

Lastly it is to be remarked that in some cases the compensating chamber 17 may be done away with at the extremity of the 110 bow and thus be confined merely to the central portion.

Claims.

1. In a semirigid airship of the character set forth including an inflatable bag 115 and a longitudinal bottom girder therein, a cruciform system of wings, each composed of fixed keel elements and of controllably movable rudder elements, and a rigid subdivided cage structure of substantially the longitudinal extent of said wing system outwardly non-rigidly mounted on the stern portion of said inflatable bag.

2. In an airship according to claim 1, the provision of a cross-stiffening means in at least one of the subdivisions of said wing-carrying cage.

3. In an airship according to claim 1,

the arrangement that the wing-carrying cage extends to the outer extremity of the stern portion of the inflatable bag.

4. In an airship according to claim 1, the provision in at least one of the cage subdivisions of a cross-stiffening structure of spider shape including spokes secured at their outer ends to said cage, and means associated with the inflatable bag for allowing said spider spokes to pass airtightly through the bag wall.

5. In the semirigid airship with a lower girder and a cruciform system of wings according to claim 1, the annular cage bearing the system of wings provided in at least one of its sections with a spider stiffening system, the elements of the cage being non-rigidly fastened to the inflatable bag by means of fabric strips secured with one of their edges to the envelope, and the free edges of said strips being fastened together above the metal element covered by them.

6. In airships according to claim 1 a com-

pensating air chamber confined towards the stern portion up to the point at which starts 25 the annular cage of the system of wings.

7. In an airship according to claim 1, the arrangement that the wing-supporting cage is limited in longitudinal extent to the length of the rigid wing portions acting 30 as keels.

8. In an airship according to claim 1, the provision of a stiffening cross-partition within the wing-supporting cage for separating the stern portion of the inflatable bag 35 back of said partition from the rest of the bag, and a gas bag within the stern chamber thus partitioned off.

In testimony whereof I affix my signature in the presence of two witnesses, at 40 Rome this twelfth day of August 1922.

UMBERTO NOBILE.
